DESIGN FOR MEDAL OR SIMILAR ARTICLE

Fred Jaske, Alameda, and Carl M. Johnson,
San Francisco, Calif.

Application April 29, 1936, Serial No. 62,382

Term of patent 3½ years

To all whom it may concern:

Be it known that we, Fred Jaske and Carl M. Johnson, citizens of the United States, residing respectively in Alameda, in the county of Alameda, State of California, and in the city and county of San Francisco, State of California, have invented a new, original, and ornamental Design for Medal or Similar Article, of which the following is a specification, reference being had to the accompanying drawing, forming part thereof.

Fig. 1 is a face view of one side of a medal showing our new design;

Fig. 2 is a face view of the side opposite to that shown in Fig. 1; and

Fig. 3 is a sectional view of the medal taken on the line 3—3 of Figure 1.

We claim:

The ornamental design for medal or similar article, substantially as shown.

FRED JASKE.
CARL M. JOHNSON.
